UNITED STATES PATENT OFFICE.

HARRY A. CHUSE, OF MATTOON, ILLINOIS, ASSIGNOR, BY MESNE ASSIGNMENTS, TO
MATTOON ENGINE WORKS, OF MATTOON, ILLINOIS, A CORPORATION OF ILLINOIS.

UNIFLOW ENGINE.

Application filed February 7, 1923. Serial No. 617,463.

The invention relates to uniflow or terminal exhaust engines in which the inlet end or ends and the cylinder head or heads are usually provided with jackets and the steam supplied to the engine is passed through the jackets to the inlet valve or valves. Difficulty, however, has been encountered in providing an arrangement that will effect such circulation of steam through the jackets that dead pockets in which condensation collects are avoided. The present improvement seeks to provide a construction which will provide for a positive circulation through all portions of the jacketing chambers and thus insure the more efficient operation of the engine and which will also permit the easy removal of the cylinder head for inspection purposes. The invention consists in the features of improvement hereinafter set forth, illustrated in the preferred form in the accompanying drawings and more particularly pointed out in the appended claims.

Fig. 1 is a view partially in elevation and partially in longitudinal section, of the cylinder of a double acting terminal exhaust engine provided with the present improved arrangement for steam jacketing the inlet ends and the cylinder heads.

Fig. 2 is a vertical transverse section taken partly on the line *a*—*a* and partly on the line *b*—*b* of Fig. 1.

The terminal exhaust engine illustrated has the usual elongated piston 1 reciprocating within the cylinder 2 which is provided with a central exhaust port 3 and with inlet ports 4 at its ends. The central exhaust port is opened and closed by the piston at the ends of its stroke and the inlet ports 4 are controlled by suitable valves, preferably in the form of poppet or lift valves 5.

The end portions of the cylinder are enlarged and cored out to form annular steam jackets 6 that surround the inlet ends of the cylinder bore. At one point, and preferably adjacent its lower side portion, each jacket is provided with a flanged steam inlet 7 and a connection 8 is secured to the inlets of both jackets and to the steam supply pipe. A portion of each jacket also communicates with the inlet valve and in the preferred arrangement shown the upper portion of each jacket is provided with a flange 9 surrounding an opening therein and to which the cap plate 10 of a bracket 11 is secured to close the opening. The brackets 11 carry the

guides for the inlet valves and portions of the mechanism by which the valves are operated and which may be of any usual or suitable type. Each steam jacket is divided into two segmental chambers by partition walls 12 which are located at approximately diametrically opposite points and at approximately equal distances from the steam inlet 7. Each steam jacket is thus divided into two segmental or substantially semi-circular chambers *c* and *d*, one of which communicates with the steam supply and the other with the inlet valve.

As usual the bore of the cylinder is slightly enlarged at its ends and hollow heads 13 fitting therein are provided with flanges 14 which overlap and are secured by a circular series of bolts 15 to the end faces of the cylinder. The abutting faces of the cylinder and flanges are quite wide and are ground as usual to form tight joints.

The outer wall of the hollow cylinder head is preferably offset inwardly from the flange and, for greater strength is connected to the inner wall by an integral, central stud 16. The flange 14 of the head is of considerable thickness and is cored out at spaced intervals between the portions of the flange containing the bolt holes to form recesses or passages 17 that communicate with the peripheral portion of the steam chamber *e* in the cylinder head. Holes drilled through the abutting joint faces of the cylinder and its head form a circular series of ports 18 that communicate with the passages 17 and thus connect the chamber *e* of the cylinder head with both of the chambers *c* and *d* of the adjacent steam jacket. In effect these ports are divided into two segmental series, one series communicating with the steam jacket chamber *c* and the other with the steam jacket chamber *d*.

With this arrangement the steam entering the inlet 7 of the steam jacket circulates through its chamber *c*, passes thence through one segmental series of the ports 18 into the chamber *e* of the cylinder head, then through the chamber and the other segmental series of ports 18 into the steam jacket chamber *d* and thus to the inlet valve. It is particularly noted that the two semi-circular series of inlet and outlet ports of the hollow cylinder head are symmetrically arranged and are uniformly distributed throughout and closely adjacent the periphery of the cylinder.

head. It is further noted that except for the central connection between the inner and outer walls of the cylinder head, that the chamber is unobstructed. Because of this arrangement the steam is uniformly distributed and positively circulated throughout all portions of the steam jacket and the hollow cylinder head, and the collection of condensation in dead spaces or pockets is avoided.

Obviously, changes may be made in the details set forth without departure from the essentials of the invention as defined in the claims.

15 I claim as my invention:

1. In a terminal exhaust steam engine, a cylinder having a steam jacket confined to and encircling its inlet end, said jacket being divided into two segmental chambers, 20 one having a steam supply, an inlet valve arranged in the other of said chambers, and a hollow head for the cylinder having a circular series of ports arranged closely adjacent the periphery of its chamber and communicating with the chambers of the cylinder jacket, the ports communicating with one of said jacket chambers being symmetrically and diametrically disposed with reference to the ports communicating with the 25 other of said chambers substantially as described.

2. In a terminal exhaust steam engine, a cylinder having a steam jacket confined to and encircling its inlet end and having partitions at approximately diametrically opposite points dividing the jacket into separate chambers, one having a steam supply inlet, an inlet valve communicating with the other of said chambers, and a hollow cylinder head the chamber of which is connected with both of the chambers of said jacket by a uniformly distributed circular series of ports located closely adjacent the periphery of the chamber of the head, substantially as 40 described.

3. In a terminal exhaust engine, a cylin-

der having a steam jacket confined to and encircling its inlet end, said chamber being divided by partitions into two segmental chambers, one having a steam inlet, an inlet valve communicating with the other chamber, and a hollow cylinder head having its inner and outer walls connected at the center and periphery of the head but otherwise having an unobstructed chamber, and said head having two, symmetrically arranged, semi-circular series of ports located closely adjacent the periphery of its chamber and communicating respectively with the separate chambers of the cylinder jacket, 55 substantially as described.

4. In a terminal exhaust engine, a cylinder having a steam jacket confined to and encircling its inlet end, said steam jacket being divided into two chambers, one having a steam inlet, an inlet valve in communication with the other of said chambers, and a hollow head fitting within the cylinder and having a flange overlapping the cylinder wall and connected thereto by a circular series of bolts extending through said flange, the flange of said head having a circular series of recesses arranged between the bolts extending therethrough and a circular series of ports connecting said passages with 70 the chambers of the cylinder jacket, substantially as described.

5. In a steam engine, a cylinder provided at its end with an inlet valve and an annular steam jacket divided into two segmental 80 chambers, one having a steam inlet and the other communicating with said inlet valve, and a hollow cylinder head having a flange overlapping and connected by a circular series of bolts to the end of the cylinder, the chamber of said head having a series of extensions at its periphery arranged between the bolts and communicating through a circular series of ports with the chambers of 85 said jacket.

HARRY A. CHUSE.
